(57) **CLAIM**

The ornamental design for a multi-orientation sonar transducer array system, as shown and described.

DESCRIPTION

FIG. 1 is a right top perspective view of a multi-orientation sonar transducer array system in accordance with an embodiment of the present invention;

FIG. 2 is a front view of the multi-orientation sonar transducer array system of FIG. 1;

FIG. 3 is a rear view of the multi-orientation sonar transducer array system of FIG. 1;

FIG. 4 is a right view of the multi-orientation sonar transducer array system of FIG. 1;

FIG. 5 is a left view of the multi-orientation sonar transducer array system of FIG. 1;

FIG. 6 is a top view of the multi-orientation sonar transducer array system of FIG. 1;

FIG. 7 is a bottom view of the multi-orientation sonar transducer array system of FIG. 1;

FIG. 8 is a right top perspective view of the multi-orientation sonar transducer array system of FIG. 1, where the multi-orientation sonar transducer array system is attached to a shaft of a trolling motor; and,

FIG. 9 is a right top perspective view of the multi-orientation sonar transducer array system of FIG. 1, where the multi-orientation sonar transducer array system is attached to a pole, such as for mounting to a watercraft.

The dash-dash broken lines illustrate environmental structure and form no part of the claimed design. The dash-dot-dash broken lines define the bounds of the claimed design and form no part thereof.

1 Claim, 8 Drawing Sheets
